UNITED STATES PATENT OFFICE.

O. W. KELLOGG, OF RIPON, WISCONSIN.

IMPROVEMENT IN ROAD-SCRAPERS.

Specification forming part of Letters Patent No. 33,650, dated November 5, 1861.

To all whom it may concern:

Be it known that I, O. W. KELLOGG, of Ripon, in the county of Fond du Lac and State of Wisconsin, have invented a new and Improved Road-Scraper; and I do hereby declare that the following is a full, clear, and exact description of the same, reference being had to the annexed drawings, making a part of this specification, in which—

Figure 1 is a plan or top view of my invention; Fig. 2, a side sectional view of the same, taken in the line α α , Fig. 1.

Similar letters of reference indicate corresponding parts in the two figures.

The object of this invention is to obtain a road-scraper of simple construction, which may be readily tilted in order to discharge its load, and also readily righted or set for filling after the load is discharged, and one in which the necessary manipulation will be attended with but little labor, while the device will be under the complete control of the operator.

To enable those skilled in the art to fully understand and construct my invention, I will proceed to describe it.

A represents a board, which forms the back of the scraper, and has a draft-pole B attached to its front side and two handles C C attached to its back part. The board A may be of any suitable or desired length, and there is a side piece D at each end of it, said side pieces forming the sides of the body of the machine when the latter is at work or in the act of scraping. The lower ends of the side pieces D D form acute angles with their front sides, and to the lower ends of the side

pieces a bottom board E is secured, the front part of which is shod with metal, as shown at a. The front edge of the bottom board may be straight, as shown in Fig. 1, or it may be rounded, as indicated by the dotted lines. The side pieces D D extend up as high as the top of the back board A, their front edges being shod with metal, as shown at b, and the back edge of board E is connected by hinges or joints a' to the lower edge of the board.

The draft-animals are attached to the machine by the side of the pole B, and as the machine is drawn along the bottom board E has an inclined position, the back edges of the side pieces D D bearing against the back board A. The dirt is scraped up by the board E, the shod portion a forming a sort of share. When a sufficient quantity of dirt has been scraped up into the body of the device, the attendant who has hold of the handles C C slightly elevates the back part of the machine and the share a of the bottom board E catches against the ground, and said board is thrown back and the front edges of the side pieces D D brought in contact with the ground, as shown in red, Fig. 2. The load is thus very readily dumped or discharged, and in order to have the parts adjusted in proper position the driver simply backs the team so that the share a will catch against the ground and the parts are thrown back to their working position.

The manipulation required to operate the machine, it will be seen, is but little and may be performed with facility and with but trifling labor, while the construction is extremely simple and durable, there being no parts liable to get out of repair nor become deranged by use.

Having thus described my invention, what I claim as new, and desire to secure by Letters Patent, is—

The bottom board E, provided with a share or shod portion a and having side pieces D D attached, in connection with the back board A, having the draft-pole B and handles C C attached to it and connected to the back edge of the bottom board E by hinges or joints a', all being arranged and combined substantially as and for the purpose set forth.

O. W. KELLOGG.
